CLAIM

We claim the ornamental design for a metal transaction device, as shown and described.

DESCRIPTION

FIG. 1 depicts a perspective view of the front face of a metal transaction device.

FIG. 2 depicts a perspective view of the rear face of the metal transaction device of FIG. 1.

FIG. 3 depicts a front elevational view of the metal transaction device of FIG. 1.

FIG. 4 depicts a back elevational view of the metal transaction device of FIG. 1.

FIG. 5 depicts a side elevational view of the metal transaction device of FIG. 1.

FIG. 6 depicts an opposite side elevational view of the metal transaction device of FIG. 1.

FIG. 7 depicts a bottom plan view of the metal transaction device of FIG. 1; and,

FIG. 8 depicts a top plan view of the metal transaction device of FIG. 1.

The broken lines in the drawings illustrate environmental structure on the article and form no part of the claimed design.
